UNITED STATES PATENT OFFICE.

ELEAZER KEMPSHALL, OF NEWTON, MASSACHUSETTS, ASSIGNOR TO
THEOPHILUS KING, TRUSTEE, OF BOSTON, MASSACHUSETTS.

DESIGN FOR A LACING-HOOK.

SPECIFICATION forming part of Design No. 25,837, dated July 28, 1896.

Application filed November 13, 1895. Serial No. 568,862. Term of patent 14 years.

To all whom it may concern:

Be it known that I, ELEAZER KEMPSHALL, of Newton, in the county of Middlesex and State of Massachusetts, have invented and 5 produced a new and original Design for Lacing-Hook Blanks, of which the following is a specification.

This invention relates to a new and original 10 design for lacing-hook blanks; and it consists in the novel features of shape and configuration hereinafter fully described and particularly claimed, and clearly illustrated in the drawings.

Reference is to be had to the accompanying 15 sheet of drawings, forming a part of this application, wherein like characters are used to indicate like parts wherever they occur.

Figure 1 represents a perspective view showing my design. Fig. 2 is a longitudinal 20 sectional view thereof.

The essential feature of my design consists in an attaching member terminating in a ring-shaped member, a neck extending from one side of said member and carrying a dome-

shaped head arranged over, a slight distance 25 from and substantially parallel to, said ring-shaped member, said dome-shaped head being formed with an aperture.

a represents the attaching member, which may be formed with one or more parts, terminating in a ring *a'*. *a²* represents a neck extending from one side of the ring *a'* and carrying a dome-shaped head *a³*, that, as shown, is arranged over a slight distance from and substantially parallel with the ring *a'*. The 35 head is formed with an aperture *a⁴*.

I claim—

The design for a lacing-hook blank, substantially as shown and described.

In testimony whereof I have signed my 40 name to this specification, in the presence of two subscribing witnesses, this 5th day of November, A. D. 1895.

ELEAZER KEMPSHALL.
